UNITED STATES PATENT OFFICE

ALBERT LINDSAY DOERING, OF GERMANTOWN, PENNSYLVANIA, ASSIGNOR TO J. S. THORN COMPANY, OF GERMANTOWN, PENNSYLVANIA, A CORPORATION OF PENNSYLVANIA

METALLIC WINDOW STRUCTURE

Application filed June 4, 1931. Serial No. 542,092.

My invention may be advantageously employed in what are known as metallic casement window structures, each comprising a stationary window frame and a hinged sash, 5 formed of oppositely counterpart wrought metal sections which, when the sash is closed, form a tubular recess extending all around the sash, said recess being closed by weathering flanges on the frame and sash.

10 As hereinafter described, my invention includes means including a handle projecting inwardly from the inner side of the stationary frame, adapted to effect adjustment of the sash to and from open and closed position, 15 when turned by the operator through an arc less than a complete revolution of said handle. Said handle is connected with a worm or spiral gear in mesh with a spiral gear, concentric with the fulcrum of a lever, which 20 fulcrum is fixed in the window frame; the opposite end of said lever being operatively connected with the sash.

An essential feature of my invention as above described is that the gearing connecting said handle with the sash is normally entirely concealed within said tubular recess formed by the frame and sash members and protected from the weather by the weathering flanges on said members.

30 My invention includes the various novel features of construction and arrangement hereinafter more definitely specified.

In said drawings: Fig. I is an inside elevation of a stationary window frame with 35 a hinged sash mounted therein and embodying a convenient form of my invention.

Fig. II is a fragmentary plan sectional view of said window structure, taken on the line II, II, in Fig. I.

40 Fig. III is a fragmentary vertical sectional view, taken on the line III, III, in Fig. II, but on a larger scale, showing the means connecting the sash operating lever in sliding engagement with the bottom rail 45 of the sash.

Fig. IV is a sectional view similar to Fig. II, but with the sash shown in open position in which the outer face of the glass in the sash is accessible from the interior of the 50 building.

Fig. V is a fragmentary vertical sectional view, taken on the line V, V, in Figs. I and II, but on the same scale as Fig. III.

Fig. VI is a fragmentary plan sectional view, taken on the line VI, VI, in Figs. I and V, on the same scale as the latter, showing the gearing indicated in Figs. II and IV.

In said figures; 1 is the stationary window frame having oppositely counterpart hinge brackets 2 and 3 respectively rigidly connected with the top rail 4 and bottom rail 5 of said frame 1 and projecting outwardly from the latter, as shown in Figs. II and IV. Said stationary hinge brackets 2 and 3 are connected by pintles 7 and 8 with respective hinge brackets 9 and 10 which are respectively rigidly connected with the top and bottom rails 12 and 13 of the sash 14 and project outwardly therefrom as shown in Figs. II and IV. Said sash is thus hinged 65 supported by the frame 1 so that when in the open position shown in Fig. IV, the plane of the sash is offset toward the middle of the frame far enough to afford access from the interior of the building to clean the outer 70 surface of the glass 15 in said sash.

As shown in Figs. II, III, IV, and V, said frame 1 is entirely formed of bars of wrought metal rolled to a substantially L-shaped cross section, such bars being mitered and joined 80 at the corners of the frame 1 by welding the ends thereof together on the lines 17 in Fig. I.

The hinged sash frame 14 is similarly formed of wrought metal bars of substantially L-shaped cross section, as indicated in 85 Figs. II, III, IV, and V. As shown in Figs. II, III, and V; when the sash frame 14 is in closed position with respect to the window frame 1, the flanges of both frames are in overlapped weathering relation inclosing 90 a tubular recess 18 between them, which recess extends entirely around said sash frame.

The purpose of the invention is to open said hinged sash 14 more or less with respect to the stationary frame 1 and hold it in adjusted position by means of the lever 20. Said lever is fulcrumed on the pivot pin 21 in the bearing 22 which is rigidly held in said frame 1 conveniently by the two screws 23. Said lever 20 is pivotally con- 100

nected at its opposite end upon the rivet 25, carried by the slide block 26. Said slide block is mounted to reciprocate in the undercut channel formed by the guide plate 27 which is rigidly connected with the lower 5 rail 13 of the sash 14, conveniently by the screws 28 indicated in Fig. II.

Said lever 20 has, rigidly connected therewith, conveniently by welding, in concentric relation with its fulcrum pin 21, the worm gear 30 engaging the worm 31. Said worm 31 has the squared end 32 set in a square socket in the hub 34 of the crank handle 35, in which it is held by the screw 36 extending 10 through the washer 37.

In the form shown, the threads on the worm 31 are of such rapid pitch that it is necessary to make but one-half revolution of said handle 35 to turn the worm gear 30 with its lever 20 through an arc of ninety 15 degrees from closed to open position of said sash frame 14, and the inclination of the threads on the worm is such that the worm may be turned by movement of the sash. Therefore, some other means are necessary 20 to hold the sash in adjusted position when such a rapid pitch worm is employed, and I provide said handle 35 with the axially adjustable set screw 39 which bears against the brake shoe 40 at its inner end so as to 25 press said shoe against the arcuate flange 41 on the stationary bearing 42 which is rigidly connected with said frame 1, conveniently by the two diametrically opposite screws 30 43, one of which is shown in Fig. I.

That construction and arrangement are such that said handle 35 and the parts connected therewith may be held in any desired 35 position of adjustment, by clamping said brake shoe 40 against said arcuate flange 41, by turning said screw 39.

However, if the threads on the worm be made of a sufficiently slow pitch that the worm cannot be turned by movement of the sash, 45 it is unnecessary to provide any other means to hold the sash or its operating handle in adjusted position.

Therefore, I do not desire to limit myself to the precise details of construction and arrangement herein set forth, as it is obvious 50 that various modifications may be made therein without departing from the essential features of my invention, as defined in the appended claims.

55 I claim:

1. In a metallic window structure, the combination with a stationary window frame; of a sash frame hinged to said window frame; the bars of said frames being 60 channels and so disposed in opposite relation that when the sash is closed in the window frame there is a tubular recess between said frames extending entirely around the sash frame and closed by the flanges on the 65 channels when overlapped in weathering re-

lation; a lever fulcrumed at one end in the recess of said stationary window frame and having its opposite end operatively connected with said sash frame; a worm gear rigidly connected with said lever, in concentric relation with its fulcrum, in said recess; a worm mounted to rotate in said recess, between said frames, and in mesh with said worm gear; and a crank handle on said worm projecting from said recess into the building, from the inner face of said window frame; whereby said sash may be openend and shut by turning said handle. 70 75

2. A structure as in claim 1; including means, adjustable independently of said worm, adapted to hold said sash in any position of adjustment. 80

3. In a metallic window structure, the combination with a stationary window frame; of a sash frame hinged to said window frame; the bars of said frames being channels, each of substantially L-shaped cross section, so disposed in opposite relation that when the sash is closed in the window frame there is a tubular recess between said frames 85 extending entirely around the sash frame and closed by the flanges on the channels then overlapped in weathering relation; a slide block; a lever fulcrumed at one end in the recess of said stationary window frame and having its opposite end pivotally connected with said slide block mounted to reciprocate in said recess in said sash frame; a worm gear rigidly connected with said lever, in concentric relation with its fulcrum, in said 90 recess; a worm mounted to rotate in said recess between said frames and in mesh with said worm gear; a crank handle on said worm projecting into the building from the inner face of said window frame; and means adjustable to hold said handle in any position of adjustment of said sash, including a set screw carried by said handle. 95 100

4. A structure as in claim 3; including a brake shoe adapted to be operated by said set screw. 110

5. A window structure as in claim 1, where- 115 in the worm and handle axis is transverse to the plane of the window frame, and the gearing connecting the crank handle with the sash is adapted to effect full opening of the sash with less than a complete revolution of said handle; whereby said handle may be located close to the sill or stool at the bottom of the window sash and within the extent of 120 the sill.

6. The combination with a window structure including a stationary window frame, and a sash frame hinged to said stationary frame, and an inwardly projecting sill; of 125 an operating handle, having its axis transverse to the plane of the window frame, mounted above said sill and within the extent of the latter; and gearing connecting said handle with said sash adapted to effect 130

full opening of said sash by approximately one-half revolution of said handle above said sill; thus avoiding projection of the sash operating mechanism beyond the sill into the building.

In testimony whereof, I have hereunto signed my name at Philadelphia, Pennsylvania, this 30th day of December, 1930.

ALBERT LINDSAY DOERING.
